SLIDABLE GOLF BALL FOR PUTTING PRACTICE

Paul D. LaHue, 5880 N. Rural, Indianapolis, Ind. 46220

Filed Nov. 7, 1969, Ser. No. 19,986

Term of patent 14 years

Int. Cl. D21—01

U.S. Cl. D34—5

Fig. 1.

Fig. 2.

Fig. 3.

Fig. 4

Fig. 5

FIG. 1 is a top plan view of a slidable golf ball for putting practice of the present invention.

FIG. 2 is a side elevation of the structure illustrated in FIG. 1.

FIG. 3 is a side elevation of the structure illustrated in FIG. 1 taken at a 90° angle to the FIG. 2 view.

FIG. 4 is a bottom plan view of the structure illustrated in FIGS. 1, 2 and 3.

FIG. 5 is a fragmentary section taken vertically through the center of the structure illustrated in FIGS. 1, 2, 3 and 4.

I claim:

The ornamental design for a slidable golf ball for putting practice, as shown and described.
